WATER REFRIGERATION

Ralph C. Roe, Englewood, N. J.

Application February 23, 1933, Serial No. 658,106

17 Claims. (Cl. 62—115)

My invention relates to improvements in water refrigeration and more particularly to improvements in water refrigeration as applied to air conditioning. Further objects of my invention are a simplification and cheapening of water refrigeration apparatus, together with increased reliability of such apparatus and ability to operate it from electrical sources. Further objects of my invention will become apparent as the specifications appear and proceed.

In the present state of the art, the vacuumization necessary for water refrigeration is nearly always performed by means of steam actuated vacuum pumps which are supplied with steam from boilers and other cumbersome and heavy equipment. Where this steam is not available, water refrigeration is not used.

In my invention, I am improving this art to permit a more universal use of water refrigeration, particularly in small sizes and for the cooling of small buildings, residences and homes.

In the figures, Figure 1 is a side schematic partial cross sectional drawing of my preferred method of water refrigeration as applied to air conditioning, Figure 2 is a cross sectional elevation of a portion of Figure 1 along lines 2—2, Figure 3 is a side schematic partial cross sectional drawing of an alternate, and in some few cases a more desirable method of utilizing water refrigeration, than in my preferred arrangement. Figure 4 is a partial cross sectional plan view of a portion of the apparatus in Figure 1, Figure 5 is a side schematic partial cross sectional drawing of an alternate method of water refrigeration which in some few cases is preferable to Figures 1 or 3. Figure 6 is a partial cross sectional view of Figure 5 along lines 6—6. Figure 7 is a plan cross sectional portion of Figure 5 along lines 7—7. Figure 8 is a detail drawing of a steam actuated jet pump similar to that used in the previous figures. Figure 9 is a cross section of a portion of Figure 8 along lines 9—9.

In the figures, 1 are fans handling air to be cooled, 2—2 are cross sectional lines in Figure 1, 3 is a heat exchanger for cooling air with cold water, 4 is a fin tube heat exchange surface in heat exchanger 3, 5 is a louver for inlet air to heat exchanger 3, 6—6 are cross sectional lines in Figure 5 referring to Figure 6, 7—7 are cross sectional lines in Figure 5 referring to Figure 7, 8 is an evaporator, 9—9 are cross sectional lines in Figure 8 referring to Figure 9, 10 are sprays in evaporator 8, 11 is water level in evaporator 8, 12 is a pump 13 circulating water from evaporator 8 through

heat exchanger 3 and spray 10, 13 is a motor driving pump 12, 14 is a conduit from pump 12 to heat exchanger 3, 15 is a conduit from heat exchanger 3 to evaporator 8, 16 is a valve controlling water supply to evaporator 8, 17 is a float controlling valve 16, 18 is a receiver working at approximately atmospheric pressure, 19 is a heat exchanger operated by fuel or any suitable source of heat, connected to receiver 18, 20 are inlet and outlet conduits for heat exchanger 19, 21 is a thermostat in receiver 18, 22 is a fuel regulating valve actuated by thermostat 21, 23 is a vent from receiver 18 to atmosphere, 24 is a heat exchanger, 25 is a conduit between valve 16 and evaporator 8, 26 is a conduit between valve 16 and heat exchanger 24, 27 is a steam actuated jet pump which is functionally similar in all figures where it is shown, 28 is a conduit between heat exchanger 24 and receiver 18, 29 is a Venturi nozzle in jet pump 27, 30 is a Venturi diffuser in jet pump 27, 31 is a throat in jet pump 27, 32 is a mixing chamber in jet pump 27, 33 is a valve, 34 is a float actuating valve 33, 35 is a conduit between heat exchanger 24 and valve 33, 36 is a conduit between valve 33 and receiver 18, 37 is a steam compressor, 38 is a motor driving compressor 37. Applying only to Figure 3, 39 is a pump, 40 is a partition, 41 is a conduit, 42 are spray nozzles, 43 is a conduit, 44 is a thermostatically controlled valve, 45 is a thermostat controlling valve 44. 46 is a suction conduit applicable only to Figures 5 and 6. Applying to all arrangements 47 is a discharge conduit from compressor 37 to jet pump 27, 48 is a conduit from evaporator 8 to pump 12, 49 is insulation on receiver 18 and connecting conduits, 50 is insulation on evaporator 8 and connecting conduits. Applying only to Figures 1 and 5, 51 are cooling fins on diffuser 30 of jet pump 27. 52 in Figure 5 is an internally finned heat transfer surface from jet pump 27 to steam space 53. 53 in Figures 1, 3 and 5 is a steam space in receiver 18, 54 are internal fins on part 52, 55 is internal fin heat transfer surface between jet pump 27 and compressor 37 in Figure 1 only, 56 are internal fins to part 55, shown in Figure 2 only, 57 is collecting header from parts 55 applying to Figures 1 and 2 only, 58 is connecting conduit from part 57 to compressor 37, applying to Figures 1 and 2 only, 59 is a distributing hood in Figure 1 only, 60 in Figures 8 and 9 are conduits supplying jet pump 27, 61 is a steam space in jet pump 27, 62 is a throat in Venturi nozzle 29 and jet pump 27, 63 is stream line insulation around conduit 60, 64 is insulation around jet 55

nozzle 29 and steam space 61, 65 is a source of water for the system such as city water, 66 is water space in receiver 18, 67 is a liquid level in receiver 18, 68 in Figure 1 is a conduit from compressor 37 to hood 69, 69 are vent holes in hood 69, 70 in Figure 8 is an entrance opening to jet pump 27, 71 is an exit opening to jet pump 27, 72 is a conduit of small size applying to Figure 3 only, 73 is a temperature regulated valve applying to Figure 3 only, 74 is a conduit, 75 is a water spray nozzle applying to Figures 3 and 8 only, 76 in Figure 3 is a feather weight non-return or check valve, 77 is a division line between aroclor and water, 78 is a space filled with 15 aroclor, 79 is a conduit from pump 39 to water space 66, 80 in Figure 3 is suction inlet of compressor 37, 81 is a thermostat controlling valve 73.

In operation, receiver 18 is filled with water from source of water 65, via heat exchanger 24, 20 conduit 35, valve 33, controlled by float 34 and via conduit 36. Heat is applied to heat exchanger 19 by gas or other heating means until sufficient of this water is heated and vaporized to reach a temperature in receiver 18 of approximately 212 25 degrees at which time thermostat 21 actuating valve 22 controls the fuel supply and maintains this temperature. When the system is in operation in its entirety, as will hereinafter be explained, the fuel supply is entirely cut off with 30 the exception of a pilot light.

For the purpose of illustration, taking my preferred method as illustrated in Figure 1, power is applied to compressor 37 from motor 38 resulting in a partial vacuumuation of evaporator 38 via jet pump 27 and interconnecting transfer surface 55. This lowers the pressure in evaporator 3, heat exchanger 3, conduits 14, 15 and 48, pump 12, jet pump 27, etc. and permits the flow of steam previously generated by action of 40 heat exchanger 19 as heretofore explained through conduit 47 and conduit 80, steam space 61 to jet pump 27. This steam passing through throat 62 of Venturi nozzle 29 and out through throat 31, diffuser 30 and heat transfer surface 45 55 58, is recompressed by compressor 37 at the same time entraining with it any gases in evaporator 3 and further vacuumizing evaporator 3 and its appurtenances. When pump 12 is started by means of motor 18, water will circulate through 50 spray 16 in evaporator 3 and will be cooled by evaporation to a low temperature. If evaporator 3 is under $29\frac{1}{2}$ " of vacuum or $\frac{1}{2}$ " Hg absolute pressure, its temperature will be approximately 55 59 degrees F. The steam emitted by said vaporization is pumped by jet pump 27 in the manner hereinbefore described and is further compressed by compressor 37 after which it passes via conduit 63 to distributing hood 59 where a portion 60 of it leaves through vent holes 60 into steam space 53 of receiver 18 and goes to the atmosphere through vent 28 and the remaining portion passes through conduit 47 to jet pump 27 and continues to operate said jet pump.

In normal operation a portion of the heat of compression passes from diffuser 30 via fins 51 and through heat transfer surface 55 and fins 56 to water in space 66, keeping this water at the boiling temperature, approximately 212 degrees, and vaporizing some portion of it. Under these conditions thermostat 21 acting through control valve 22 cuts all the fuel off of heat exchanger 19 except for a pilot light. It is thus seen that the use of fuel by heat exchanger 19 70 75 is confined to starting and standing periods.

The operation of steam impelled jet pumps is well known in the art and these pumps can be designed under favorable conditions for high efficiencies. In the design of these pumps, the design of Venturi nozzle 29 and throat 62, the pitch of the Venturi nozzle and their relation in length with themselves and with each other are well known in the art on account of the vast experience in turbine nozzle design and the efficiency can be calculated to a high degree of accuracy 10 and this portion of the device can be designed with high efficiency. The same may be said of throat 31 and diffuser 30. One of the sources of inefficiency of jet pumps has been the handling in the mixing space 32 of two different kinds of 15 elastic fluids, usually steam as an impelling fluid and air as the fluid to be pumped, or in some cases steam as an impelling fluid and steam-air mixtures as the fluid to be pumped. This has been largely eliminated in my device by predesignating the steam supply to the jet pumps by the heating of water in space 66 and the venting of the emitted entrained gases through vent 23 and therefore it is possible to design jet pumps 20 25 for this service with somewhat higher efficiencies than has heretofore been the case.

A further source of inefficiency has been the admixture of an impelling fluid as steam with the fluid to be impelled, whether it may be steam or air, of entirely different characteristics such as the mixture of steam emitted from Venturi nozzle 29 superheated or with a large percentage of moisture in it, and trying to mix this in mixing space 32 with saturated steam at the corresponding pressure. It is generally conceded that 30 the most perfect mixtures and therefore the highest efficiencies can be obtained by the mixing of two fluids of the same characteristics or if the characteristics must be different, with a moderate degree of supersaturation in the case of the 40 impelling fluid (steam).

In my system, it is possible by properly coordinating steam compressor 37, the amount of heat transfer surface 55, and other design features to provide pressures and temperatures of 45 steam entering jet nozzle 62 which will allow expansion of steam in Venturi nozzle 29 entering the mixing space 32 with the quality and character designed to give the maximum efficiency. The low pressure steam entering the steam jet 50 pump 27 at entrance 70, particularly when dealing with large volumes as will be the case with high vacuums, should enter directly and with as little loss as possible due to turns or swirls. This has been provided for in the design of my jet 55 pump 27 and steam conduit 68 has been insulated not only to prevent heat loss and the consequent expansion and change in quality of the vapor to be compressed, but also in a stream 60 line form to allow these conduits to interfere only to the minimum degree with the flow of vapors to be compressed. It is therefore seen that the coordinated arrangements of my device between steam compressors and jet pumps 65 and heating surface distribution permits a steam jet pump design of an efficiency which has heretofore been impractical.

In the operation of jet pumps, the compression is generally adiabatic or nearly so and when compressing saturated steam from approximately $\frac{1}{2}$ " Hg absolute to 4" Hg absolute, which would be a reasonable duty for the jet pump in Figure 1, the temperature of the compressed steam would be slightly over 400 degrees with reasonable effi- 70 75 78 80 82 84 86 88 90 92 94 96 98 99 100

ciency of said jet pump. If this temperature can be reduced by heat exchange through fins 51 and heat exchange surface 55, with 212 degrees water in space 66, the overall pumping efficiency of the combined jet pump and compressor will be much improved because of the reduction in volumes entailed by the reduction in temperature. This is the purpose of this surface and the compression tends to depart from the adiabatic a slight way toward the isothermal. Compressor 37 and a portion of conduit 68 are also submerged for the same purpose, all of which has a beneficial effect on the efficiency of the refrigerating system as a whole, compressor 37 having a working duty in the illustration I have chosen in Figure 1 of from 4" Hg absolute to 30" Hg absolute pressure of 14.7# absolute.

In the other figures, the duty of the jet pumps and compressors are different from the one just discussed as will hereinafter be explained.

As the water continues to evaporate in evaporator 8, it must be replenished and provision is made to do this via conduit 28, heat exchanger 24, regulating valve 16 and conduit 25. Water is taken from water space 66 by this arrangement and is therefore water which has been heated and consequently deaerated. Such water entering evaporator 8 is cooled by heat exchanger 24 by the incoming water used to replace it and is desirable for use in evaporator 8 because it will not emit any appreciable quantity of non-condensable gases when vaporized.

The heat exchange surface fins 56 are installed for the purpose of increasing the heat transfer on heat exchange surface 55 to thereby improve the overall efficiency of the apparatus.

The air transferred by fans 1 from louvers 5 over radiating surface 4 of heat exchanger 3 is cooled by the removal of its heat and the absorption of said heat in heat exchanger 3 and is in some cases dehumidified by the reduction of temperature below the dew point of the air.

In Figure 3, the operation is similar to that of Figure 1 but different in some respects. In this case, jet pump 27 has a duty from 1/2" Hg absolute pressure to atmosphere or 30" Hg absolute pressure and the compressor 37 takes steam via inlet 80 at the pressure and temperature of the discharge of jet pump 27 and therefore compresses it to a point where it can act as an impelling fluid for said jet pump. For the purpose of illustration, we will assume this compression to be up to 65# absolute. Steam then passes through conduit 47 to jet pump 27 as before and performs the vacuumizing duty on evaporator 8 in a similar manner as previously described. Pump 39 takes water from water space 66 via conduit 79 and sprays a large portion of it via conduit 41 and through sprays 42, this serving to produce very good deaeration of the water and to remove

60 in a thorough manner all entrained gases. A minor portion of this water passes through conduit 43, valve 44, to the suction of compressor 37. The compression of steam by compressors follow in general along adiabatic lines and the temperature would go quite high with a corresponding consumption of power without cooling. In order to match the temperatures most advantageous for the operation of jet pump 27, to properly cool compressor 37 and to improve the efficiency of compressor 37, water is introduced in the suction of this compressor as heretofore explained. In a similar manner, in compressing steam from 1/2" Hg absolute pressure to 30" Hg absolute pressure in jet pump 27 of Figure 3 very high temperatures would be produced particularly with

the range of pressure involved and considerable power would be used in producing these high temperatures. To decrease this power and to improve the efficiency of jet pump 27, I have introduced water via conduit 72, valve 73, conduit 74 and nozzle 75 into mixing chamber 32 of jet pump 27. This water is vaporized by the heat hereinbefore mentioned and in so doing reduces the net power or work required for the operation of jet pump 27 and also reduces the amount of power required per pound of steam actually pumped by said jet pump from evaporator 8 to receiver 18.

To illustrate the magnitude of the benefits just described, it is assumed for the purpose of illustration, that jet pumps can be constructed with 100% efficiency. In that case, with steam entering jet pump 27 at 1/2" Hg absolute pressure as in Figure 3, in a dry saturated condition and being compressed to atmospheric pressure or 30" Hg absolute by adiabatic compression (constant entropy), the energy required for this compression will be approximately 400 B. t. u. and the resultant final temperature would be in the neighborhood of 900 degrees F. For the expenditure of energy of the aforesaid 400 B. t. u. there would be compressed 1 pound of steam from the vaporization of 1 pound of water to vapor at 1/2" Hg absolute to 30" Hg absolute. The latent heat of vaporization at 1/2" Hg is approximately 1059 B. t. u. and therefore the theoretical ratio would be 2.64 B. t. u. absorbed by evaporation for each B. t. u. expended in compression. In a similar manner if there is put into jet pump 27 via spray nozzle 75, .165# of water mixed with .835# of water vapor, the energy required to compress this mixture from 1/2" Hg to 30" Hg on the same basis would be approximately 240.5 B. t. u. The heat absorption in the evaporator per pound of this mixture would be $1059 \times .835 = 844.26$ which divided by 240 gives a ratio of B. t. u. required for energy for compression as against B. t. u. absorbed in the evaporator per pound of 3.67 to 1, a considerable gain as compared with the previous example without cooling of 2.64 to 1. The efficiencies of the jet pumps in the two cases would be similar and therefore the above gives a reasonably true indication of the magnitude of the saving to be accomplished by this arrangement. Inasmuch as the energy for actuating the jet pump all comes from compressor 37 in the form of power, this is directly reflected in the power consumption of the refrigerating device.

Partition 40 allows an adjustment of temperatures between exhaust of jet pump 27 and intake of compressor 37 and the water distribution in the pump and compressor in the most advantageous manner.

In Figure 5, jet pump 27 has a similar duty to that in Figure 3 and compresses steam from evaporator 8 to receiver 18 with a duty of approximately from 1/2" Hg absolute to 30" Hg absolute pressures. The heat of compression in this case is absorbed by water in space 66 by means of fins 51 and heat absorbing surface 52 and fins 54 therein. Compressor 37 works in the same manner as in the previous case with the exception that it is submerged for its cooling effect and does not have water actually mixed with the steam it is compressing. The results obtained with the proper distribution of heat exchange surfaces can be greatly similar to the results obtained with the arrangement in Figure 3.

In accordance with drawing, Figure 3, I have shown a means to provide a cooling and lubricat-

ing fluid around compressor 37. For this fluid I prefer aroclor (chlorinated diphenyl), a high boiling point hydro-carbon heavier than water and non-miscible therewith, an excellent lubricant, a good conductor of heat and a good electrical insulator. The submerging of compressor 37 in this fluid prevents corrosion of the iron and steel parts, permits the pumps to be built with proper lubricating openings and permits the 10 aroclor to lubricate these pumps via such openings. In cases where driving motor is located internal to the device, it is also submerged in aroclor and the aroclor acts as an insulating fluid for the same. The material being heavier than 15 water will stay in the position indicated and any portion passing through the compressor will return to the said position. The high boiling point of the substance prevents its escape by vaporization and therefore little, if any, of this substance 20 is lost.

The heated surfaces of these devices are insulated with material suitable for withstanding heat and the cooled surfaces are insulated with material suitable for this purpose.

25 While I have shown and described one embodiment of my invention in accordance with the patent statutes, and have shown the important modifications thereto, and explained in detail the function of the various parts of the apparatus so 30 that one skilled in the art can understand the apparatus, it is understood that my invention is capable of embodiment in a variety of forms of apparatus and I am not limited to the specific 35 form of arrangement or structural parts shown and described but that the scope of my invention is to be gauged by the accompanying claims taken in connection with prior art.

I claim:

1. In a water refrigeration system, an evaporator in heat transfer relation with a fluid to be cooled, a receiver, water disposed in said evaporator and said receiver, vaporizing means for water, vapor compressing means limited to actuating fluid only, vapor pressure actuated jet 40 pumping and vacuumizing means between said evaporator and said receiver, said jet pumping and vacuumizing means being in actuating relation with said vapor compressing means, venting means for said receiver, liquid supply means to 45 said evaporator.

2. In a water refrigeration system, an evaporator in heat transfer relation with a fluid to be cooled, a receiver, water disposed in said evaporator and said receiver, vaporizing means for water, vapor compressing means limited to actuating fluid only, vapor pressure actuated jet pumping and vacuumizing means between said evaporator and said receiver, said jet pumping and vacuumizing means being in actuating relation with said vapor compressing means, heat 50 exchange means between water in said receiver and vapors compressed by said vacuumizing means, venting means for said receiver, liquid supply means to said evaporator.

60 3. In a water refrigeration system, an evaporator in heat transfer relation with a fluid to be cooled, a receiver, water disposed in said evaporator and said receiver, vaporizing means for water, vapor compressing means limited to actuating fluid only, heat exchange means between vapor compressed by said compressing means and water in said receiver, vapor pressure actuated jet pumping and vacuumizing means between 65 said evaporator and said receiver, said jet pump-

ing and vacuumizing means being in actuating relation with said vapor compressing means, venting means for said receiver, liquid supply means to said evaporator.

4. In a water refrigeration system, an evaporator in heat transfer relation with a fluid to be cooled, a receiver, water disposed in said evaporator and said receiver, vaporizing means for water, vapor compressing means limited to actuating fluid only, heat exchange means between 10 vapor compressed by said compressor and water in said receiver, vapor pressure actuated jet pumping and vacuumizing means between said evaporator and said receiver, said jet pumping and vacuumizing means being in actuating relation with said vapor compressing means, heat exchange means between water in said receiver and vapors compressed by said vacuumizing means, venting means for said receiver, liquid supply means to said evaporator.

15 5. In a water refrigeration system, an evaporator in heat transfer relation with a fluid to be cooled, a receiver, water disposed in said evaporator and said receiver, vaporizing means for water in said evaporator, vaporizing means for water in said receiver, thermostatic control means for said vaporizing means, vapor compressing means limited to actuating fluid only, vapor pressure actuated jet pumping and vacuumizing means between said evaporator and said receiver, heat exchange means between water in said receiver and vapors compressed by said vacuumizing means, venting means for said receiver, liquid supply means to said evaporator.

25 6. In a water refrigeration system, an evaporator in heat transfer relation with a fluid to be cooled, a receiver, water disposed in said evaporator and said receiver, vaporizing means for water, vapor compressing means limited to actuating fluid only, vapor pressure actuated jet pumping and vacuumizing means between said evaporator and said receiver, said jet pumping and vacuumizing means being in actuating relation with said vapor compressing means, cooling 30 means cooling vapors compressed by said vacuumizing means, venting means for said receiver, liquid supply means to said evaporator.

35 7. In a water refrigeration system, an evaporator in heat transfer relation with a fluid to be cooled, a receiver, water disposed in said evaporator and said receiver, vaporizing means for water, vapor compressing means limited to actuating fluid only, cooling means for cooling vapors 40 compressed by said compressing means, vapor pressure actuated jet pumping and vacuumizing means between said evaporator and said receiver, said jet pumping and vacuumizing means being in actuating relation with said vapor compressing means, venting means for said receiver, liquid supply means to said evaporator.

45 8. In a water refrigeration system, an evaporator in heat transfer relation with a fluid to be cooled, a receiver, water disposed in said evaporator and said receiver, vaporizing means for water, vapor compressing means limited to actuating fluid only, cooling means for vapor compressed by said compressing means, vapor pressure actuated jet pumping and vacuumizing 50 means between said evaporator and said receiver, said jet pumping and vacuumizing means being in actuating relation with said vapor compressing means, cooling means cooling vapors compressed by said vacuumizing means, venting means from 55 70 75 80 85 90 95 98 99

said receiver, liquid supply means to said evaporator.

9. In a water refrigeration system, an evaporator in heat transfer relation with a fluid to be cooled, a receiver, water disposed in said evaporator and said receiver, vaporizing means for water, vapor compressing means limited to actuating fluid only, liquid injection cooling means in said compressing means, vapor pressure actuated jet pumping and vacuumizing means between said evaporator and said receiver, said jet pumping and vacuumizing means being in actuating relation with said vapor compressing means venting means from said receiver, liquid supply means to said evaporator.

10

15

10. In a water refrigeration system, an evaporator in heat transfer relation with a fluid to be cooled, a receiver, water disposed in said evaporator and said receiver, vaporizing means for water, vapor compressing means limited to actuating fluid only, vapor pressure actuated jet pumping and vacuumizing means between said evaporator and said receiver, liquid injection cooling means in said vacuumizing means, venting means for said receiver, said jet pumping and vacuumizing means being in actuating relation with said vapor compressing means, liquid supply means to said evaporator.

30 11. In a water refrigeration system, an evaporator in heat transfer relation with a fluid to be cooled, a receiver, water disposed in said evaporator and said receiver, vaporizing means for water, vapor compressing means limited to actuating fluid only, liquid injection cooling means
35 for said compressor, vapor pressure actuated jet pumping and vacuumizing means between said evaporator and said receiver, liquid injection cooling means in said vacuumizing means, venting means from said receiver, said jet pumping
40 and vacuumizing means being in actuating relation with said vapor compressing means, liquid supply means to said evaporator.

45 12. In a water refrigeration system, an evaporator in heat transfer relation with a fluid to be cooled, a receiver, water disposed in said evaporator and said receiver, vaporizing means for water, vapor compressing means limited to actuating fluid only, liquid injection cooling means in said compressing means, thermostatic means controlling said liquid, vapor pressure actuated jet pumping and vacuumizing means between said evaporator and said receiver, said jet pumping and vacuumizing means being in actuating relation with said vapor compressing means, venting means for said receiver, liquid supply means to said evaporator.

50

55

60 13. In a water refrigeration system, an evaporator in heat transfer relation with a fluid to be cooled, a receiver, water disposed in said evaporator and said receiver, vaporizing means for water in said vaporator, vaporizing means for water in said receiver, vapor compressing means limited to actuating fluid only, vapor pressure actuated jet pumping and vacuumizing means be-

tween said evaporator and said receiver, said jet pumping and vacuumizing means being in actuating relation with said vapor compressing means, liquid injection cooling means in said vacuumizing means, thermostatic means controlling said liquid, venting means for said receiver, liquid supply means to said evaporator.

14. In a water refrigeration system, an evaporator in heat transfer relation with a fluid to be cooled, a receiver, water disposed in said evaporator and said receiver, vaporizing means for water in said evaporator, vaporizing means for water in said receiver, vapor compressing means limited to actuating fluid only, liquid injection cooling means for said compressor, thermostatic means controlling said liquid, vapor pressure actuated jet pumping and vacuumizing means between said evaporator and said receiver, said jet pumping and vacuumizing means being in actuating relation with said vapor compressing means, liquid injection cooling means in said vacuumizing means, thermostatic means controlling said liquid, venting means for said receiver, liquid supply means to said evaporator.

15. In a water refrigeration system, an evaporator in heat transfer relation with a fluid to be cooled, a receiver, water disposed in said evaporator and said receiver, vaporizing means for said water, deaerating means for said water, vapor compressing means limited to actuating fluid only, vapor pressure actuated jet pumping and vacuumizing means between said evaporator and said receiver, said jet pumping and vacuumizing means being in actuating relation with said vapor compressing means, venting means for said receiver, liquid supply means to said evaporator. 25 30 35

16. In a water refrigeration system, an evaporator in heat transfer relation with a fluid to be cooled, a receiver, water disposed in said evaporator and said receiver at predetermined levels, 40 vaporizing means for said water, vapor compressing means limited to actuating fluid only, vapor pressure actuated jet pumping and vacuumizing means between said evaporator and said receiver, said jet pumping and vacuumizing means being in actuating relation with said vapor compressing means, level regulated liquid supply means to said receiver, level regulated liquid supply means from said receiver to said evaporator, venting means for said receiver. 45 50

17. In a water refrigeration system, an evaporator in heat transfer relation with a fluid to be cooled, a receiver, water disposed in said evaporator and said receiver, vaporizing means for said water, vapor compressing means limited to actuating fluid only, vapor pressure jet pumping and vacuumizing means between said evaporator and said receiver, said jet pumping and vacuumizing means being in actuating relation with said vapor compressing means, venting means for said receiver, liquid supply means to said receiver, liquid supply means from said receiver to said evaporator, heat exchange means between the said two liquid supply means. 55 60
